UNITED STATES PATENT OFFICE.

MILON J. TRUMBLE, OF ALHAMBRA, CALIFORNIA, ASSIGNOR TO McEVoy WIRELESS WELL STRAINER CO., OF LOS ANGELES, CALIFORNIA, A CORPORATION OF CALIFORNIA.

WELL-SCREEN.

1,210,020.

Specification of Letters Patent. Patented Dec. 26, 1916.

Application filed May 31, 1916. Serial No. 100,987.

To all whom it may concern:

Be it known that I, MILON J. TRUMBLE, a citizen of the United States, residing at Alhambra, in the county of Los Angeles and State of California, have invented a new and useful Well-Screen, of which the following is a specification.

My invention relates to the art of pumping oil or water from the ground, and particularly to the art of protecting the pumps used from the action of foreign matter.

The principal object of my invention is to provide a well screen which may be secured around a pipe projecting into a well or sump, for the purpose of screening or straining out large particles of sand or gravel which would otherwise pass into the interior of the pipe and impede the action of the pump, or cause excessive wear thereon.

In the drawings, which are for illustrative purposes only: Figure 1 shows an elevation of the lower portion of a pump column equipped with my invention, a portion of the jacket being broken away to better illustrate the internal structure. Fig. 2 shows a view on an enlarged scale of one set of perforations.

In the form of the invention illustrated in the drawings, a pipe column 11 is provided with a plurality of round holes 12, these holes being preferably drilled in standard or extra heavy pipe at regular intervals therearound. Secured around the column 11, by any convenient means, is a steel jacket 13, this jacket having a series of series of narrow slots 14 cut therein, each of these series being so placed as to exactly cover or register with one of the holes 12.

In practice, the column 11 will consist of ordinary steel pipe, and the jacket 13 will be of thin galvanized iron, or some similar material. The jacket 13 may be secured by various means, such as rivets or by means

of solder, but I prefer to secure it by electrically welding the jacket 13 along its upper edge 15, its lower edge 16, and along a seam 17. The jacket can also be secured by a series of spot welds produced electrically at various points between the jacket 13 and the pump column 11.

I claim as my invention:

1. A well screen comprising a pipe having circular perforations therein, and a thin sheet metal jacket secured to said pipe and provided with a series of series of narrow slotted openings, each of said series being so placed as to register with one of said circular perforations in said pipe.

2. A well screen comprising a pipe having circular perforations therein, and a thin sheet metal jacket formed of a single sheet of metal bent around and secured to said pipe and provided with a series of series of narrow slotted openings, each of said series being so placed as to register with one of said circular perforations in said pipe.

3. A well screen comprising a pipe having circular perforations therein, and a thin sheet metal jacket secured by having its edges welded to said pipe and provided with a series of series of narrow slotted openings, each of said series being so placed as to register with one of said circular perforations in said pipe.

4. A well screen comprising a pipe having circular perforations therein, and a thin sheet metal jacket formed of a single sheet of metal bent around and secured by having its edges welded to said pipe and provided with a series of series of narrow slotted openings, each of said series being so placed as to register with one of said circular perforations in said pipe.

In testimony whereof, I have hereunto set my hand at Los Angeles, California, this 24th day of May, 1916.

MILON J. TRUMBLE.
